UNITED STATES PATENT OFFICE.

ABRAHAM L. ADAMS AND GEORGE E. HAWES, OF BRIDGEPORT,
CONNECTICUT.

MACHINE FOR CUTTING, FOLDING, AND WINDING STRIPS OF FLEXIBLE MATERIAL.

SPECIFICATION forming part of Letters Patent No. 581,015, dated April 20, 1897.

Application filed July 6, 1896. Serial No. 598,227. (No model.)

To all whom it may concern:

Be it known that we, ABRAHAM L. ADAMS and GEORGE E. HAWES, citizens of the United States, residing at Bridgeport, in the county 5 of Fairfield and State of Connecticut, have invented certain new and useful Improvements in Machines for Automatically Cutting, Folding, and Winding Strips of Flexible Material; and we do hereby declare the following to be a full, clear, and exact description of the invention, such as will enable others skilled in the art to which it appertains to make and use the same.

Our invention relates to certain improvements in machines for automatically cutting, 15 folding, and winding strips of flexible material so that such strips may be available for use in the form of spools; and our invention consists in the details of construction and 20 in the operation of various instrumentalities such as will be hereinafter fully set forth, and then specifically designated by the claims.

In the accompanying drawings, which form a part of this application, Figure 1 is a plan 25 view of our newly-invented machine; Fig. 2, a side elevation; Fig. 3, a section at the line *a a* of Fig. 1; Fig. 4, a section at the line *b b* of Fig. 3; Fig. 5, a section at the line *c c* of Fig. 3; Fig. 6, a section at the line *d d* of Fig. 30 1; Fig. 7, a detail sectional elevation, on an enlarged scale, showing the operation of the rollers which effect the creasing, folding, and ironing functions; Fig. 8, a sectional elevation similar to Fig. 3, but showing a modification of our invention in which the ironing-roller is dispensed with; and Fig. 9, a sectional elevation similar to Fig. 3, but showing a modification of our invention in which the 35 creasing, folding, and ironing rollers are omitted, the machine thus simplified being especially adapted for cutting and winding plain unfolded strips.

Similar numbers of reference denote like parts in the several figures of the drawings. 45 There are three groups of mechanisms that are identified with our invention, and each group performs its function independent of the others, and although we prefer to associate these mechanisms in a single machine, 50 so that we may obtain the best results, never-

theless we do not wish to be confined to such association, since our invention is broad enough to include each one of such mechanisms separately and distinctly. In other words, each mechanism, by the elimination 55 of the other two mechanisms, is enabled to perform its individual function and constitutes a machine in itself producing a useful result. These three mechanisms to which we have referred are, first, the cutting or slitting 60 machine, by means of which the strips are cut from a solid width of material; second, the folding mechanism, whereby the lateral edges of the strips are folded over upon the body of the strip; third, the winding mech- 65 anism, by means of which the finished strips are wound upon spools.

For a better understanding of our invention we will describe these several mechanisms consecutively, but we will first call attention to the general form of the machine and its adaptation to such mechanisms. 70

1 is the frame of the machine, which is supported in any usual manner, as by legs 2, and 75 3 is the bed or table.

4 is the power-shaft, which carries the power-pulley 5.

The cutting mechanism comprises two rolls 6 7, journaled within the frame of the machine one above the other, each roll carrying 80 a series of cutter-disks 8 9, which respectively engage each other after the manner of a pair of shears. These disks are separated by a space equal to the full width desired of the strips, and rigid with said rolls 6 7 are intermeshing spur-gears 10 11, one of which gears also meshes with a gear 12, carried by the power-shaft 4, so that it will be clear that the proper revolution of the cutter-rolls will be effected directly from the power-shaft. 85

A piece of fabric or other suitable material of the desired width being placed upon the table 3 and led between the rolls 6 7, it will be manifest that as this fabric passes between the rolls it will be cut or slitted into a gang 95 of strips, which latter are then engaged by the mechanisms for creasing, folding, and ironing such strips, which mechanisms we will now describe.

13 14 are rolls journaled within the frame 100

of the machine and carrying intermeshing spur-gears 15 16, one of which latter is also engaged by the gear 12 on the power-shaft. The roll 13 has in its periphery a series of annular grooves 17, whose width is equal to the width of the folded strip, and the roll 14 carries a series of peripheral collars 18, which fit snugly within said grooves.

19 is the ironing-roller, which is journaled within a frame 20, which latter at its lower end is pivoted around the shaft of the roller 14, while its outer extremity carries a resilient plug 21, which rests upon an adjusting-screw 22, driven through an ear 23, rising from the frame of the machine. This ironing-roller is beyond the rolls 13 14 and is elevated so that its upper circumference is considerably above the lower circumference of the roll 13, and such ironing-roller carries a gear 25, which meshes with the gear 15^a and also carries a series of peripheral collars 24 of such width as to fit snugly within the grooves of the roller 13.

As the strips already cut, in the manner hereinbefore set forth, pass between the rollers 13 14 the collars on the roller 14 will force the strips within the grooves of the roller 13, thereby causing the edges to be creased, so as to lie flat against the side walls of the grooves, and the tension on the creased strips as the latter are deflected upward around the bottoms of the grooves will draw the creased edges down flat against the bodies of the strips, and the roller 19 will then act against these folded edges to firmly iron them into place. The pressure of the ironing-roller may be regulated by the adjusting-screw 22.

It will be observed that there is a space between the points of contact which the rollers 14 19 have with the roller 13, and the object 40 of this of course is to enable the creased edges of the strip to be drawn down flat against the body of the strip by the upward deflection of the latter around the roller 13, so that said edges may be properly disposed before they 45 are brought in contact with the ironing-roll, and right here in this connection we would say that this manner of drawing down the edges of the strips preparatory to ironing is a very important feature of our invention, since 50 we are enabled thereby to dispense with any special appliance for performing the folding operation.

The folded and finished strips are passed over the top of the ironing-roller to the winding mechanism, a description of which latter we will now give.

26 is a guide-roller journaled in the frame of the machine, and having in its periphery a series of grooves 27 just wide enough to contain the folded strips.

28 is a spindle journaled within the upper end of a frame 29, the lower end of which latter is pivoted around the power-shaft 4. On this spindle are keyed a series of spools 65 30, corresponding in number to the number of strips, and each spool is slotted in its periphery, as seen at 31, within which slotted

portions the extremities of the strips are forced for the purpose of securing the latter during the winding operation.

The folded strips are passed within the grooves 27 and are seened to the spools, and as the strips are wound on said spools the coiled-up portions of said strips will extend within said grooves and will be supported by the bottoms of the latter. As the strip-rolls increase in diameter during the winding operation the contact between the strip-rolls and the guide-roller will be constant, owing to the fact that the frame 29 will be gradually elevated by reason of the gradually-increasing distance between the spindle 28 and the guide-roller. The side walls of the grooves 27 cause the strips to be wound in vertical planes, while the contact between the strip-coils and the guide-roller causes the winding to be effected tightly. Upon the extreme outer end of the frame 29 a weight 32 is placed to increase the frictional contact between the guide-roller and the strip-coils, and this weight may be varied as the occasion demands or it may be dispensed with altogether, if desired.

The spindle 28 is made in two sections, one of which terminates in a socket 33, while the other section is bifurcated, as shown at 34, and fixed within said socket, a pin 35 being driven laterally through said socket and within said fork, whereby the two sections of the spindle are secured together as to rotary motion, while at the same time the section which carries the spools may be readily withdrawn by grasping the handle 36 for the purpose of removing the spools.

Of course it will be clear that as the diameters of the strip-rolls increase the revolution of such rolls would tend to draw a longer length of strip, and we therefore belt up the spindle to the power-pulley, making use of frictional devices of very ordinary construction, so that the full benefit of the driving-belt cannot be exerted to revolve the spindle. Without going into any details of explanation of such a very ordinary mechanical expedient we will merely say that the socket-section of the spindle carries a shoulder-collar 37, while around such section is a loose disk 38, which abuts against said collar. A collar 39 is splined on said section, so as to be capable of a movement lengthwise thereof, and interposed between this collar and disk 38 is a leather washer 40, a nut 41 being driven on the extreme end of said section and a coil-spring 42 being interposed between said nut and collar 39, so that when the nut 42 is driven inward the disk 38 will be bound between the shoulder 37 and collar 39, the friction between such parts being sufficient to cause the spindle to be revolved when power is applied to the disk 38. A belt is run from the power-pulley around said disk, and when the tendency of the winding-spools is to take up a greater length of strip than is cut and folded the disk 38 will simply slip around

the collar 37 without effecting a corresponding revolution of the spindle.

The surfaces of the various portions of the several rollers which come in contact with the strips may be serrated or roughened, if desired, in order to obtain a better grip on the strips, and in the instance of certain materials of which the strips are composed this may be deemed necessary; but we do not desire to be limited in this respect, as this is a precautionary measure rather than a necessary adjunct of our invention.

There is a great difference between fabrics and other materials of which the strips are composed, and some of these will become cockled or distorted more readily than others, and we have therefore provided certain devices which we will now describe and which greatly assist in properly delivering and guiding the cloth during the various operations hereinbefore set forth.

Resting immediately upon the table in front of the cutting-rollers is what we term a "guide-plate" 43, upon whose upper surface are two series of ribs 44 45, one of such series being on one side of a vertical plane which intersects the cutting-rollers crosswise at their middle portions and the other series of such ribs being on the opposite side of such plane. These two series of ribs are each inclined from their outer extremities inwardly toward said plane and at the same angle thereto, and the cloth as it is delivered to the cutting-rollers rests immediately upon said guide-plate. Should it be discovered that the cloth was being fed out of true or in a direction a little to one side, the operator simply places his hand upon the cloth and presses it lightly against the ribs of the guide-plate, which incline in the direction opposite to that in which the cloth is being improperly shifted, and this will immediately correct the error, and by practice an operator may readily correct any inaccuracy in the feeding of the cloth.

Rising from the table immediately in the rear of the creasing-rollers and at the extreme opposite sides of such table are twin spindles 46, and between these spindles is a vertical plate 47, of metal, which rests by its gravity like a straight-edge immediately upon such table. The strips pass from the cutters immediately beneath this plate, and any cockling or twisting of such strips is smoothed out by the plate prior to the delivery of the strips to the creasing, folding, and ironing rollers.

We are enabled to obtain the best results by making the effective diameters of all the positively-moving rollers the same and by so gearing them that their speeds will likewise be the same, for by so doing there can be no dragging of the strips or of the cloth through any of the rollers and the cloth or other material cannot possibly become distorted.

It will be manifest that some of the mechanisms of our improved machine may be changed and others may be entirely omitted without departing from the spirit of our in-

vention, to some of which changes and omissions we will now call attention.

The guide-roller is not at all necessary to the manufacture of the strips, and, moreover, while a most excellent contrivance, need not be used at all times, especially in instances where the spools themselves have flanged sides. The ironing-roller, while it is really necessary in the instance of most fabrics, can be entirely dispensed with at times, especially when the strips can remain in coiled form before using a sufficient length of time to enable the folded portions to "set."

In Fig. 8 we have shown a modification of our improvement in which the ironing and guide rollers are entirely dispensed with and the strip led farther around the upper creasing-roll and upwardly to the winding-spool, which latter in this instance is supported almost immediately above such roll in order to allow the strip to have this additional lap around the latter.

Some strips are used without folded edges, and heretofore these strips have been cut and wound upon spools in a very crude and imperfect manner, but our invention naturally suggests a very practical and effective way of cutting and winding such strips, it being necessary merely to omit the rollers which effect the creasing, folding, and ironing of the edges. We have therefore shown in Fig. 9 a modification of our improved machine in which the guide-roller is indispensable in connection with the winding-spool. Referring to this Fig. 9, we would say that the construction, assembly, and operation of all the parts shown are precisely the same as hereinbefore set forth, with the exception that the guide-roller carries a pulley 48 and the power-shaft a pulley 49, which pulleys are connected by belt 50, so that it will be clear that a positive revolution is imparted to the guide-roller directly from the power-shaft.

As hereinbefore set forth, the winding-roll has a tendency to drag the strips through the cutting-rollers, and this tendency is of course resisted in our construction above described by the creasing and ironing rollers, which maintain quite a bite upon the strips. In the present instance the tendency of the winding-spools to revolve too fast is checked by the uniformly-speeded guide-roller, which latter, by the way, moves at precisely the same rate of speed as do the cutter-rollers. Therefore it will be clear that when the speed of the winding-spools is checked the disk 38 will slip in the manner before described, while the speed at which the strips are wound will always be the same and will always correspond with the speed at which such strips are cut.

While we prefer that the cutter-rollers and the creasing, folding, and ironing rollers should all be capable of rotation, in order that the strips may pass through these rollers positively and without any tendency to drag, nevertheless all of such rollers may

be stationary and the strips may be pulled therethrough by the winding devices, and we therefore do not wish to be limited in this respect.

5 Having thus described our invention, what we claim as new, and desire to secure by Letters Patent, is—

1. In a machine of the character described, the combination of a pair of rollers having 10 complementary collars and grooves for creasing the strips, and means for deflecting the creased strips at a tension toward the axial horizontal plane of the grooved roller whereby the creased edges are folded, substantially as 15 set forth.

2. In a machine of the character described, the combination of a pair of rollers having complementary collars and grooves for creasing the strips, means for deflecting the creased 20 strips at a tension toward the axial horizontal plane of the grooved roller whereby the edges of the strips are folded, and means for ironing down said folded edges, substantially as set forth.

25 3. In a machine of the character described, the combination of a pair of rollers having complementary collars and grooves for creasing the strips, means for deflecting the creased strips at a tension toward the axial horizontal 30 plane of the grooved roller whereby the edges of the strips are folded, a roller for ironing down said folded edges, a series of winding-spools upon which said strips are wound in coils, and a guide-roller provided with peripheral grooves, said coils extending within said 35 grooves and resting by gravity against the bottoms thereof, substantially as set forth.

4. In a machine of the character described, the combination of a pair of rollers journaled 40 one above the other and carrying complementary cutter-disks, a pair of rollers journaled one above the other and carrying complementary collars and grooves for creasing the strips, an ironing-roller whose upper surface 45 is considerably elevated above the lower sur-

face of the upper creasing-roller and is in close proximity to the effective periphery of such creasing-roller, whereby the creased strip is deflected against the rounded surface of such upper roller and subsequently ironed down, and means for winding the folded strips, substantially as set forth. 50

5. In a machine of the character described, the combination of a pair of rollers having 55 complementary collars and grooves for creasing the strips, and an ironing-roller whose upper surface is considerably above the bottom of the upper creasing-roller while the effective peripheries of said ironing-roller and upper creasing-roller are in close proximity 60 to each other, substantially as set forth.

6. The combination of the winding-spools journaled within a frame capable of a free vertical movement upon which spools the strips are wound in coils, and the guide-roller having 65 a series of peripheral grooves, said coils extending snugly within said grooves and resting by gravity against the bottoms thereof, substantially as set forth.

7. The combination of the cutter-rollers 70 having a uniform and positive rotation, the winding-spools journaled in a frame capable of a free vertical movement upon which spools the strips are wound in coils, the guide-roller having a series of peripheral grooves within 75 which said coils depend and rest by gravity against the bottoms of such grooves, the power-shaft, a friction-coupling between said shaft and the shaft of the spools, and means for imparting to the guide-roller a constant 80 and uniform speed corresponding to that of the cutter-rollers, substantially as set forth.

In testimony whereof we affix our signatures in presence of two witnesses.
